CLAIM

The ornamental design for a combined shipping container and cocktail preparation package, as shown.

DESCRIPTION

FIG. 1 is a front elevational view of a combined shipping container and cocktail preparation package showing my new design;

FIG. 2 is a top plan view thereof;

FIG. 3 is a right side elevational view thereof, the left side view being a mirror image;

FIG. 4 is a bottom plan view thereof; and

FIG. 5 is a cross-sectional view thereof taken along line 5—5 of FIG. 2.
